Des. 62,362

UNITED STATES PATENT OFFICE.

WILLIAM B. JAMES, OF LOS ANGELES, CALIFORNIA.

DESIGN FOR A CONTAINER FOR TOILET CREAMS AND THE LIKE.

Application filed March 17, 1922. Serial No. 1,221. Term of patent 14 years.

To all whom it may concern:

Be it known that I, WILLIAM B. JAMES, a citizen of the United States, residing at Los Angeles, in the county of Los Angeles and State of California, have invented a new, original, and ornamental Design for Containers for Toilet Creams and the like, of which the following is a specification, reference being had to the accompanying drawing, forming part thereof.

Fig. 1 is a front elevation, and
Fig. 2 is a rear elevation.

I claim:

The ornamental design for a container for toilet creams and the like, as shown.

WILLIAM B. JAMES.
